UNITED STATES PATENT OFFICE.

JOSEPH OLIVER CORMIER, OF CLEVELAND, OHIO.

GARMENT-FORMER.

1,245,193.

Specification of Letters Patent.

Patented Nov. 6, 1917.

Application filed February 23, 1915. Serial No. 9,847.

To all whom it may concern:

Be it known that I, JOSEPH OLIVER CORMIER, a citizen of the United States, residing at Cleveland, in the county of Cuyahoga and State of Ohio, have invented certain new and useful Improvements in Garment-Formers, of which the following is a specification.

My invention relates to steam-ironing devices, and the invention is of special utility in drying and ironing gloves, mittens, socks, stockings and like wearing apparel in a rapid and expeditious manner without scorching or otherwise injuring the article regardless of its fineness of texture and at a nominal cost in the consumption of fuel and in time and labor.

This invention is primarily designed for the use of a manufacturer, cleaner and laundress who requires a rapid, safe and efficient means of drying and ironing such articles as gloves, socks, etc., either after the manufacture of the goods or after washing or dyeing the articles in small or large quantities. The conception involves a device conforming in shape to the article to be dried or ironed and of the same or slightly smaller dimensions than the article so that a perfect or substantially snug fit may be obtained when the article is drawn thereover, and the device comprises means to distribute steam heat at a high temperature and in a safe and guarded way uniformly to the article or in such manner that the article will be uniformly dried and ironed while in place on the device and while placing it upon and removing it from the device.

In the accompanying drawings, Figure 1 is a side elevation of three of my improved devices mounted on a table and connected with steam supply and exhaust pipes and showing a sectional view of a screwing device for the steam on the supply line. Figs. 2 and 3 are transverse sections of the glove ironer on lines 2-2, and 3-3, respectively, of Fig. 4. Fig. 4 is a longitudinal section of the glove ironer, and Fig. 5 is an edge elevation thereof, Fig. 6 is a side elevation, partly in section, of a sock ironer embodying my invention, and Fig. 7 is a transverse section thereof on line 7-7, Fig. 6.

The invention comprises a hollow casing 2 made of relatively thin sheet metal, preferably brass, and containing a coil of copper pipe 3, of relatively small diameter having the respective ends thereof extending

through the bottom end of the casing and provided with suitable couplings 4 adapted to make a steam-tight connection with the valve fitting 5 of the steam supply pipe 6 and with the fitting 7 of the steam outlet pipe 8. A base member 9 having a flat extension 10 is projected into the hollow bottom and of casing 2 to provide a rigid support therefor, and any suitable means may be employed to fasten the base member 9 in a fixed position on a table or bench 11. The casing is flat on both sides and relatively shallow, being in fact made to bear against and contact with opposite sides of the pipe 3 and the entering and outgoing portions of the pipe have a still greater surface engagement with the casing in view of their corner seating position within the rounded edge portions 14 of the casing, see Figs. 2 and 7. The flat supporting extension 10 practically closes the bottom end of the casing, but a narrow space 15 is left at each side opposite the straight portion of the pipe 3 to permit the escape of and to direct any escaping steam downward and away from the operator. Such escape of steam can only occur if a leak occurs in the pipe as it is not intended to have the casing interior directly exposed to the steam. Such exposure is expressly avoided by the use of the pipe as one object of the invention is to avoid excessive heating of the brass casing or facing 2 by the steam and possible scorching and injury to the article stretched in tight and close-fitting position upon and against the casing. Steam at a high temperature and under considerable pressure may be confined safely in the copper pipe and the heat radiated by the pipe is indirectly conveyed to the goods after diffusion through the brass casing from the linear contact of the pipe at spaced intervals within the casing. The most delicate fabrics are quickly dried and ironed, but not injured if permitted to remain on the device for a reasonable period of time beyond the time necessary to get the desired results, and to understand the efficacy and need of a factor of safety in this direction it must be realized that articles such as gloves vary greatly in color, grade and character of materials. One object of the device is to do the work quickly on any article of wearing apparel made of textile or leather, or thin or heavy goods, and at the same time absolutely avoid injury when any one of these materials is subjected to a

longer period of heating than the chosen article requires.

In Fig. 4, the form and shape of casing 2 is made to correspond to that of a glove, less the thumb, and the pipe 3 is in the form of a coil having its sections following the border edges of the casing and the fingers 16, except that the central section 17 of the coil extends in the form of a loop down into the central portion of the casing to more uniformly distribute the heat to the flat body thereof corresponding to the palm and back of the glove. Extension 10 of the base support is in this case bifurcated as shown to provide a stable and stiff core for the otherwise light and hollow casing. The doubled sections 18 of the pipe 3 within the fingers 16 are also retired inwardly from the edges 19, thereby affording edge channels lengthwise at each side of the fingers to accommodate the accordion seam portions of certain types of gloves.

In Fig. 6, I show a sock form of casing, that is, the casing is made to conform to the outlines of a sock or stocking and the pipe 3 follows one border edge of the casing into the toe end 20 thereof and has a series of coils 21 extending back to the bottom, one of said coils 21 being projected into the heel portion 22 of the casing.

The pipes 3 are relatively small in diameter to limit the amount of steam passing therethrough and in a sense to regulate the maximum amount of steam which can be used without danger to the goods, and in order to avoid clogging of the pipe, I pro-

vide a tubular connection 23 for the intake end of the supply pipe which contains a screen or guard of fine wire mesh 24 of conical form whereby all foreign matter is prevented from entering the pipes. A valve 25 controls the amount of steam supplied to all the devices connected to pipe 6, and a valve 26 controls the exhaust end of pipe 8, and each device also has a valve 5 of its own at its intake end, see Fig. 1.

In drying dyed articles with my invention, the color and luster of the dye is brought to the surface and set and not deadened, lost or impaired, while the material remains soft and pliable and does not become hard.

What I claim is:—

As a new article of manufacture, a garment former comprising a thin metallic body formed in one piece having flat sides and rounded border edges, a continuous relatively small fluid conveying passage in contact with the walls of said body and having separate terminals projecting from the lower end of said body and provided each with a coupling nut affixed rotatably in sealing relations thereon, and a support for said body having a portion extending within the body and provided with a lateral projection adapted to be attached to a fixed support.

In testimony whereof I affix my signature in presence of two witnesses.

JOSEPH OLIVER CORMIER.
